MAGAZINE PENCIL

James A. Van Norsdall, Vancouver, Wash.

Application September 27, 1935, Serial No. 42,479

3 Claims. (Cl. 120—17)

My invention relates to improvements in means for operating or controlling the propulsive mechanism of magazine pencils, and consists in providing at the point of the pencil barrel, in proximity to the lead, a tapper. This tapper is movable parallel to the axis of the barrel. When it is moved inwardly of the barrel it releases the propulsive mechanism allowing the lead to emerge from the point of the barrel. The object 10 of the tapper is to avoid the necessity for shifting the position of the pencil while writing when it is desirable or necessary to manipulate the propulsive mechanism in order to have additional lead emerge from the barrel.

15 In the drawing I illustrate an embodiment of my invention which will serve to explain the principle and construction thereof.

20 In the drawing, Figure 1 is a side elevation of my invention. This figure illustrates the pencil in writing position, with the lead broken at the point of the barrel.

25 Figure 1A is a side elevation. This figure illustrates a step in the operation of renewing the lead at the point of the barrel after it has been broken.

Figure 2 is a longitudinal sectional view of the invention.

Figure 3 is a section indicated by section line 3—3 in Figure 2.

30 Figure 4 is an enlarged side elevation of the tapper bar removed from the barrel.

35 In the drawing, numeral 1 indicates the barrel of a pencil embodying my invention. This barrel is in two sections held together by a nipple 2. The lower end of the barrel terminates in a taper or point 3 in which is an opening 4 to the interior of the barrel. The head or upper end is rounded and closed with the exception of an opening 5 to the interior of the barrel. Nipple 40 2 is interiorly tapered at each end as indicated by numerals 6 and 7, which internal tapers form cams whose purposes will be described later. Mounted within the lower portion of the barrel is the tapper rod 8 having a flaring lower end

45 9 situated exterior to such barrel, and a flange 10 at its upper end situated within nipple 2. A longitudinal passage 11 extends lengthwise of the tapper rod. The upper end of the rod has a number of radial bores 12 extending from interior passage 11 to the exterior, and in these bores seat the balls 13. Tapper rod 8 cannot be pushed entirely into the barrel for the reason that the flare 9 is larger than the opening 4 within which the rod operates. Likewise the upper end cannot 50 be withdrawn from the interior of nipple 2 for

the reason that the flange 10 cannot pass the taper face 7. Further construction in tapper rod 8 consists of a longitudinal slot 14 over which is disposed a spring member mounted upon the rod. This spring member is inclined to spring 5 away from the rod at its lower end, but is prevented by the inner tapered wall of tapered end 3 of the barrel. The lower end of the spring has a tooth 16 directed toward the interior of the tapper rod.

Cooperating with tapper rod 8 is a release rod 17 which is seated coaxially in the barrel with its upper end projecting therefrom through the passage 5. The lower end has a flange 18 and terminates within nipple 2 below seat 6, which seat prevents removal of the flanged portion from the nipple. Extending longitudinally of rod 17 is a substantially elongated slot 19 which opens out from opposite sides of said rod. Penetrating the bottom of the rod and extending to and communicating with slot 19 is a passage 20 which is coaxial with passage 11 in rod 8. Operating within passage 11 and passage 20 and to a considerable extent in slot 19 is a propeller bar 21 terminating at its upper end in a T head 22 projecting from the lateral openings of such slot 19. Between the T head and the upper end of the barrel and coiled about rod 17 is an expansion coil spring 23 which urges bar 21 downwardly. In the lower end of the bar are a number of radial openings 24 leading to passage 20 from the exterior which constitute seats for balls 25. Between the flanged ends 10 and 18 and coiled about bar 21 is an expansion coil spring 26 urging members 10 and 17 apart and causing balls 13 and 25 to engage cams 7 and 6 respectively and be moved inwardly in their respective seats until they engage the bar 21.

In operation a lead 30 is inserted into the passage 11 of member 8, at the same time member 17 is pressed downwardly by pressing upon its exterior end 29. The latter movement lowers the balls 25 below cam 6 allowing them to emerge somewhat from their seats 24. Bar 21 is thus released allowing it to be raised upon insertion of lead 30. After insertion of the lead member 17 is released and further upward movement of bar 21 is restrained by reason of the fact that upon release of member 17 it is moved upwardly by spring 26, causing the balls 13 to engage cam 6 which moves them toward and into gripping engagement with bar 21. Upward movement of bar 21 compresses spring 23. The urge of the spring is to expand and unresisted would move bar 21 downward, but this is prevented by fric- 55

tionally engaging balls 13. These balls are pressed against bar 21 by cam 7 as tapper rod 8 is urged downwardly by spring 26. Upward movement of tapper rod 8 releases the balls 13 somewhat as they are allowed to move away from such bar 21. Concisely, balls 25 prevent upward movement of bar 21 by a friction grip which is released by downward movement of rod 17, and balls 13 prevent downward movement of bar 21 by a friction grip which is released by an upward movement of rod 8. The tooth 16 serves to prevent lead 30 dropping from passage 11 in the event it is somewhat loose therein by biting into such lead, this it does only when tapper rod 8 is in lowered position as the inclined walls interiorly of end 3 serve as a cam forcing the spring 15 inwardly when the tapper rod is lowered, and permitting the spring to move outwardly and the tooth to disengage the lead when the tapper rod is raised.

Often in writing with a magazine pencil the lead is broken necessitating shifting such pencil in order to manipulate control means for ejecting additional lead. Shifting is not required in the present pencil. This is illustrated in Figures 1 and 1A. In the first figure the projecting lead has been broken as shown at 31. The person employing the pencil need not shift it in his hand, but merely tips it somewhat more toward the writing surface as shown in Figure 1A. At the same time the tapper 9 is pressed upon an object, the writing surface for instance, this moves the tapper bar upwardly in the barrel, thus releasing balls 13 from their frictional grip with bar 21 and allowing such bar to propel the lead downwardly. This movement of the tapper bar also releases the tooth 16 from engagement with the lead as heretofore explained. By reason of the inclination of the pencil the lead can emerge but a short distance until it is stopped by the writing surface or the object engaged by the tapper 9. The operation just described is a mere tipping and pressing movement of the hand holding the pencil and takes but a moment of time and ensuring but a slight interruption in writing.

Having described my invention, I claim—

1. In a magazine pencil, the combination of a barrel terminating in a writing point, a tapper

rod coaxial with the barrel having a portion projecting from the point and having a longitudinal passage for carrying a lead, a release rod coaxial with the barrel and having a portion projecting from the upper end of the barrel and having a passage at one end, a propelling bar operating in both passages, means urging the bar downward, gripping members carried by the release rod resisting an upward movement of the propelling bar releasable upon downward movement of such release rod, and gripping means resisting downward movement of the propelling bar releasable by moving of the tapper rod inwardly.

2. In a magazine pencil, the combination of a barrel having a pointed lower end, a tapper rod having a lead passage slidably mounted in the lower end of the barrel, a spring urged propelling rod projecting into the upper end of the lead passage, a grip holding the propelling rod against propulsive movement releasable by moving the tapper rod upwardly, a release rod operable through the upper end of the barrel, and a grip holding the propelling rod against repulsive movement releasable by moving the release rod downwardly.

3. In a magazine pencil, the combination of a barrel having a pointed lower end, a tapper rod movably mounted in the lower portion of the barrel and projecting from the point and having a passage for lead, a release rod movable within the upper portion of the barrel and projecting from the top thereof, a spring urged propelling rod seated in the upper end of the tapper rod and the lower end of the release rod, spring means between the release rod and the tapper rod urging them in opposite directions, ball seats in the upper end of the tapper rod, balls in the seats, cam means engaged by the balls and causing them to grip and secure the propelling rod against propulsive movement and releasable when said tapper rod is moved against said spring means, ball seats in the lower end of the release rod, balls in the latter seats, and cam means engaged by the latter balls and causing them to grip and secure the propelling rod against repulsive movement and releasable when the release rod is moved against said spring means.

JAMES A. VAN NORSDALL.
